UNITED STATES PATENT OFFICE.

AMANUEL O. FORD, OF INDIAN SPRINGS, TENNESSEE.

STREET-SWEEPER.

No. 866,452.

Specification of Letters Patent.

Patented Sept. 17, 1907.

Application filed October 12, 1904. Serial No. 228,142

To all whom it may concern:

Be it known that I, AMANUEL O. FORD, a citizen of the United States, residing at Indian Springs, in the county of Sullivan, State of Tennessee, have invented 5 certain new and useful Improvements in Street-Sweepers; and I do hereby declare the following to be a full, clear, and exact description of the invention, such as will enable others skilled in the art to which it appertains to make and use the same.

10 This invention relates to sweeping machines and particularly to that class employed for sweeping streets, the object of the invention being to provide a construction which may be attached to the rear of a cart or wagon and drawn after it, the machine operating to 15 collect and elevate the dirt and discharge it into the wagon or cart.

20 A further object of the invention is to provide a construction wherein the parts may be adjusted to compensate for wear and to suit different conditions of operation, other objects and advantages of the invention being understood from the following description.

25 In the drawings forming a portion of this specification and in which like numerals of reference indicate similar parts in the several views, Figure 1 is a top plan view of a machine embodying the present invention. Fig. 2 is a side elevation of the machine unattached to a cart. Fig. 3 is a vertical section taken longitudinally through the machine attached to a cart. Fig. 4 is a transverse vertical section on line 4—4 of Fig. 1.

30 Referring more particularly to the drawings, the present machine comprises a frame including side sills 5 and 6, which are connected at their ends by the cross-pieces 7 and 8. The axle 9 of the machine is disposed towards the rear end of the frame and carries 35 upon its reduced ends the traction wheels 10 and 11, which are rotatably mounted thereon, the hub of the last-mentioned wheel being connected by a sleeve 11' with a gear 12, likewise rotatably mounted on the axle end, so that rotation of the wheel 11 will effect the rotation of the gear wheel 12.

40 At each side of the frame of the machine is a forked hanger comprising a lower stem portion 13 and upper laterally spaced members 14 and 15 in which latter are formed arc-shaped slots 16 and 17 through which 45 are passed set-screws 18 and 19 which are engaged with the adjacent sill of the frame. In the lower portions or stems of the hangers are formed bearings 20 and 21 which receive the trunnions 22 and 23 at the ends of the drum 24 of a brush. The brush includes the central drum 24 which is in the form of a polyhedron of any desired number of sides, the trunnions 22 and 23 having disks 25 and 26 at their inner ends which are secured to the ends of the drum in any suitable man-

ner. Against each face of the drum or against certain faces as preferred are disposed wisps or splints 27 which 55 lie transversely of the face and project therebeyond at both ends.

Transversely of the wisps and longitudinally of the drum are disposed clamping bars 28 of wood or other suitable material held to the drum by screws or bolts 60 29 and which clamp the wisps firmly to the drum, those faces of the drum having no wisps being provided with filling-bars 30 which serve to hold the ends of the wisps or splints so that they radiate from the drum.

The trunnion 23 is squared at its outer end beyond 65 the hanger and upon this squared portion is slidably engaged a pinion 31, the hub 32 of which is provided with a circumscribing groove in which is engaged the yoke 33 at the lower end of a lever 34 which is pivoted to an ear 35 on the adjacent hanger. The lever is provided with the ordinary latch 36 for engagement with a notched plate 37 which projects from the hanger. As the lever is shifted, the pinion 31 is swung into and out of engagement with the gear-wheel 12 to receive motion therefrom at times so that the brush may be 75 rotated or not as desired. As the machine progresses, the brush rotates with its lower side forwardly or in the direction of progress of the machine and as the hangers are adjustable vertically, the brush may be lowered to compensate for wear or raised to suit conditions of 80 use.

Coupling means 40 are connected to the front end of the frame of the machine and are pivotally engaged with a plate 41 by means of a removable pin 42. The plate 41 is secured to a cart or wagon 43 so that the machine may be drawn along the street to be swept.

In order that the dirt swept by the brush, may be elevated and discharged into the wagon or cart, an elevating apron 44 is provided, this apron, which is endless, being passed around rollers 45 and 46. The roller 46 is 90 of small diameter and is journaled in hangers 48 secured to the sides of the machine frame in such position that the apron will move very close to the ground at this point. The shaft of the drum or roller 46 being provided with a sprocket wheel or belt-wheel 49 with 95 which is engaged a chain or belt 50 engaged also with a sprocket wheel or belt wheel 51 carried by the brush trunnion 23 so that as the machine progresses, the upper side of the apron will move upwardly and forwardly. The upper roller or drum is mounted in arms 53 which 100 extend upwardly and forwardly from the frame of the machine, this upper drum being positioned to lie above the cart or wagon to discharge thereto. The dirt directly from the brush, is received by what may be termed a pan in the form of a convex plate or curved 105 plate which is disposed between the lower portion of

the apron and the bottom of the brush, the upper edge or this plate lying above the lower portion of the apron so that the dirt which is swept over the plate will pass from it onto the apron and upwardly upon the apron

- 5 to the wagon or cart, movement of the dirt with the apron being insured by cleats 54 secured transversely of the apron. The curved plate is shown at 55 and is pivoted upon a shaft 56 which is mounted in the hangers 48. The plate is free to swing toward and away 10 from the brush at its lower end and to hold the plate yieldably with its rear or lower edge against the ground, helical springs 56' are attached to the plate and to the lower ends of the hangers.

To prevent dirt passing around with the brush, a 15 curved guard-plate 60 is provided which is disposed above the first-named plate, the upper edge portion of the guard plate being bent rearwardly in the direction of the brush, in close relation to which it lies. The guard plate is provided with ears 60' at its ends which are 20 slotted to receive guide pins 61 and set screws 62 which permit of adjustment of the plate toward and away from the brush when desired and at other times serve to hold the plate in fixed position.

Upon the rear portion of the frame is mounted a seat 25 63 and the guard plate is provided with wings 64 at its ends, which extend in the direction of the brush shaft or drum at the ends of the brush.

In practice, modifications of the specific construction shown may be made and any suitable materials and proportions may be used for the various parts without departing from the spirit of the invention.

What is claimed is:—

A street sweeper comprising, in combination, a frame; an axle carried by said frame at the rear end thereof; traction wheels rotatably mounted upon the ends of said axle; a vertically adjustable fork-shaped hanger secured to each side of said frame and comprising a pair of upper, laterally-spaced members each provided with a curved slot, and a lower stem portion provided with a bearing; set-screws carried by said frame on opposite sides thereof and projecting through the slotted members of the hangers, to retain the latter in adjusted position; a rotatable brush disposed in advance of said axle, said brush being provided with trunnions adapted to fit in said bearings; a gear rotatably mounted upon said axle adjacent one of said traction wheels and connected to the hub of the latter, so as to rotate therewith; a pinion longitudinally movable upon the adjacent brush trunnion; means for moving said pinion into and out of engagement with said gear; and means carried by said frame for discharging the dirt swept up by said brush during its rotation.

In testimony whereof, I affix my signature, in presence of two witnesses.

AMANUEL O. FORD.
